US00D893496S

(12) **United States Design Patent** (10) **Patent No.:** **US D893,496 S**
(45) **Date of Patent:** **** Aug. 18, 2020**

(54) **COMPONENT OF AN ELECTRONIC DEVICE**

(71) **Applicant:** **Apple Inc.**, Cupertino, CA (US)

(72) **Inventors:** **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US); **Houtan Farahani**, San Ramon, CA (US); **Stephen Jayanathan**, Oakland, CA (US); **Christine Laliberte**, San Francisco, CA (US); **Matthew William Blum**, San Francisco, CA (US); **Ari Parsons Miller**, San Francisco, CA (US); **David P. Tarkington**, Sunnyvale, CA (US); **Edward T. Sweet**, San Francisco, CA (US); **Derryk Davis**, Cupertino, CA (US)

(73) **Assignee:** **Apple Inc.**, Cupertino, CA (US)

(**) **Term:** **15 Years**

(21) **Appl. No.:** **29/718,684**

(22) **Filed:** **Dec. 27, 2019**

(57) **CLAIM**

The ornamental design for a component of an electronic device, as shown and described.

DESCRIPTION

FIG. 1 is a perspective view of a component of an electronic device showing our new design;

(Continued)

FIG. 2 is a left side view thereof;
 FIG. 3 is a right side view thereof;
 FIG. 4 is a top view thereof;
 FIG. 5 is a bottom view thereof;
 FIG. 6 is a front view thereof;
 FIG. 7 is a rear view thereof; and,
 FIG. 8 is a another perspective view thereof.
 The dashed broken lines represent structure or features that form no part of the claimed design.

1 Claim, 6 Drawing Sheets

Related U.S. Application Data

division of application No. 29/574,932, filed on Aug. 19, 2016, now Pat. No. Des. 825,570, which is a division of application No. 29/519,784, filed on Mar. 8, 2015, now Pat. No. Des. 767,572.
